Des. 110

E. P. Pennington Rochester New York.
(assignee of Cheney, Hunter & Rowles)
Letters Patent (Design No. 110) dated 10th Feby. 1847

The schedule referred to in these Letters Patent and making part of the same.

To all whom it may concern: Be it known that I Elijah
P. Pennington of the City of Rochester, in the County of Monroe and State of New York have invented a new ornamental design for a cocking Stone, and I do hereby declare that the following is a full and exact description of the same.

The nature of my invention is fully represented on the drawings accompanying.

Fig 1st is an elevation of the side of the Stone showing the ornamentation

Fig. 2. Shows the Cap as represented A Fig 1. when looking directly down upon it

What I claim as my invention and desire to secure by Letters Patent is the ornamental design as herein represented and described
